CLAIM

The ornamental design for a simulative newspaper receptacle, as shown and described.

DESCRIPTION

FIG. 1 is a perspective view of a simulative newspaper receptacle showing my new design;

FIG. 2 is a top view thereof;

FIG. 3 is a bottom view thereof;

FIG. 4 is a front view thereof;

FIG. 5 is a side view thereof;

FIG. 6 is an end view thereof; and,

FIG. 7 is an opposite side view of that which is shown in FIG. 5.

The broken line showing of the newspaper and post shown in FIG. 1 is for illustrative purposes only and forms no part of the claimed design.
